UNITED STATES PATENT OFFICE.

ROBERT OTIS BOARDMAN, OF GRAND RAPIDS, MICHIGAN, ASSIGNOR TO MERGEN-
THALER LINOTYPE COMPANY, A CORPORATION OF NEW YORK.

TYPOGRAPHICAL MACHINE.

1,075,138.

Specification of Letters Patent.

Patented Oct. 7, 1913.

Application filed September 11, 1912. Serial No. 719,821.

To all whom it may concern:

Be it known that I, ROBERT OTIS BOARDMAN, a citizen of the United States, and a resident of Grand Rapids, county of Kent, and State of Michigan, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine in the order in which their characters are to appear in print, and then assembled in line, the composed line transferred to the face of a mold, the mold filled with molten metal to form a slug or linotype against the matrices which produce the type characters thereon, and the matrices thereafter returned through a distributing mechanism to the magazine from which they started.

More particularly, it relates to machines of the kind wherein are employed a distributing mechanism and a plurality of magazines in connection therewith, and means designed to transfer the matrices from the distributing mechanism to the proper magazine. In the present instance these transferring means are in the form of a movable conductor or holder, to which the matrices are delivered by the distributing mechanism, and in which they are temporarily held and subsequently delivered to the appropriate magazines. The movement of the intermediate conductor or holder is controlled by the form of the type or matrices contained therein, these being suitably varied in accordance with their particular font and the magazine in which it is stored, in such manner that the conductor or holder will be shifted to varying extents, in order to register with the selected magazine.

In the accompanying drawings, I have shown my invention in preferred form and by way of example, and as applied to a linotype machine. Obviously, however, many variations and alterations may be made therein, and in its mode of application, without departure from the spirit of my invention. Thus, it may be applied to typographical machines of other kinds, such as type setters and type casters, or those which handle type or dies instead of matrices.

Generally speaking, I desire it to be understood that I do not limit myself to any specific form or embodiment, except in so far as such limitations are specified in the claims.

Referring to the drawings: Figure 1 is a transverse vertical section through a portion of a linotype machine, equipped with a plurality of magazines and having my invention applied thereto; Fig. 2 is a similar view, showing the parts in different positions; Fig. 3 is an edge view of certain parts thereof; Figs. 4, 5 and 6 are detail views; and Fig. 7 illustrates a variety of matrices of different fonts as contained in the respective magazines.

As is usual in linotype machines, the matrices X are moved by the distributor screws A along the distributor rail A¹, from which they are released at the proper points and pass through the intermediate holder or conductor B into one or another of the magazines C. In the present instance, the magazines are five in number, and in Fig. 7 are shown five different forms of matrices X corresponding thereto, it being noted that each is formed with a differential cut or notch X¹ of a depth corresponding to its particular font and magazine. The holder or conductor B is pivotally mounted, as at B¹, on the frame of the machine, in such manner that it may be rocked into registration with any one of the magazines C. It will be noted that there is such a conductor or holder for each channel of the selected magazine, and that they may be individually and independently shifted by the mechanism subsequently to be described.

Each of the conductors or holders B is provided near its lower end with a releasing device, similar in form and arrangement to an ordinary escapement, it comprising a pivoted lever D and the two connected pawls D¹ capable of alternate projection into the conductor, the lower pawl D¹ being normally held in operative position by the spring D² bearing against the lever D. The withdrawal of the lower pawl and the projection of the upper pawl into the conductor is effected by the rearward movement of the reciprocating arm E connected by the link E¹ to the lever D. The series of arms E are pivotally mounted at E¹ and are operatively moved by a corresponding series of eccentrics F, a series of springs F¹ serving to

hold the arms in contact with the eccentrics and to move them in the opposite direction. As the matrices X drop from the distributing mechanism into the receiver or holder, they are temporarily held therein by the devices just described, and subsequently released thereby into their appropriate magazines.

In order to effect the correct registration of the conductor B with the selected magazine C, each conductor carries a pivoted arm J (see also Fig. 5) formed with a locking head J², which engages with one or another of a series of teeth K formed upon the framework, the said teeth being proportioned and located in such manner as to hold the conductor in operative relation to the several magazines.

Each conductor B is provided with a longitudinally movable plunger or feeler G (see also Fig. 6) arranged to work in and out of the conductor so as to contact with the edge of the lowermost matrix therein, it being normally held in its outermost or inoperative position by the spring G¹. The previously described reciprocation of the arm E effects the pivotal movement of the conductor B in such manner as to bring the end of the plunger G into engagement with the fixed stop H on the frame of the machine. This contact forces the plunger into the conductor and into the characteristic notch X¹ of the lowermost matrix, the depth of the notch determining the extent of movement of the plunger. The plunger G is also formed with a projecting shoulder G² in position to engage the shoulder J¹ of the pivoted arm J, and consequently the outer end of the latter will be elevated thereby to an extent proportionate to the movement of the plunger G, which is dependent upon the form of the lowermost matrix, as before stated. Accordingly, on the return movement of the conductor, the locking head J² will engage with the proper tooth K so as to arrest the conductor in operative relation to the magazine corresponding to the lowermost matrix, as hereinafter more particularly described.

Located on the framework beyond the stop H is the pawl L (see also Fig. 4) provided with the inclined surface L³ adapted to contact with the end of the arm J, when the latter is moved forward by the pivotal movement of the conductor B. The pawl L is pivoted at L⁴ and is held in its rigid or operative position by a spring L², the surface L³ being located so that the end of the arm J contacts therewith just before the plunger G hits the stop H. The effect of this contact is to depress the forward end of the arm J and bring it to its lowermost position. The forward end of the arm is provided with a transverse projection piece J³, and when the plunger G hits the stop H

the projection rises behind the pawl L, which is bifurcated as at L⁴ to receive the shank portion of the arm J. When the conductor B and arm J make their return movement, the projection J³ swings the pawl L out of the way against the force of the spring L², as shown by dotted lines in Fig. 1.

In order to hold the locking head J² in the position to which it is moved by the contact of the plunger G with the stop H, and thus to insure its engagement with the selected tooth K, the arm J is provided with a suitably curved spring clip or detent M which presses on the correspondingly shaped surface M¹ on the conductor B, which surface may be serrated if desired to insure a firmer engagement.

As before noted, the rearward motion of the arm E, which returns the conductor B, effects the disengagement of the lower pawl D¹ from the matrix next to be delivered, and it is accordingly necessary that other means be provided to hold the matrix until the conductor arrives at the proper magazine. To this end, on the arm J is slidably mounted the longitudinally movable piece N, formed with an end N² adapted to project into the conductor below the lowermost matrix (see Fig. 1), and having a spring N¹ to hold it normally in this position. The other end of the slide N is formed with a shoulder N³, located in proximity to the locking head J² and adapted to engage the selected tooth K slightly in advance thereof, in such manner that when the conductor B arrives in the desired position, the engagement of the shoulder N³ with the tooth withdraws the end N² from beneath the lowermost matrix, and permits it to fall into the magazine.

The operation of the parts will now be clearly understood: As the matrices pass from the distributing mechanism into the conductor B, they are temporarily held and stored therein by the escapement pawls D¹. The forward movement of the arm E swings the conductor about its pivot, the first brings the end of the arm J into contact with the inclined surface L³ of the pawl L, whereby the end of the lever J is moved to its lowermost position and beyond the pawl, and next brings the plunger G into engagement with the stop H, whereby the plunger is moved to the extent permitted by the characteristic notch X¹ of the lowermost matrix, thus effecting the upward movement of the arm J so as to bring its locking head J² into position to engage the selected tooth K, and its projection J³ behind the pawl L. This position of the parts is shown in Fig. 1. The return movement of the conductor B now begins, the first effect of which is to swing the pawl L out of the way, as shown by dotted lines in Fig. 1. The rearward movement of the arm E also withdraws the

lowermost pawl D¹ from the conductor, and the matrix would be free to drop therefrom were it not for the presence of the end N² of the slide N. The return movement of the 5 conductor continues, until the locking head J² engages with its tooth K, thus arresting the conductor B in operative relation to the corresponding magazine, which is shown in Fig. 2 as the outermost one. Just before 10 the parts reach this position, the shoulder N³ of the slide N contacts with the tooth and withdraws its end N² from the conductor, leaving the lowermost matrix free to descend into its channel. During this return movement 15 of the parts, the arm J and its locking head J² are held in adjusted position by the engagement of the clip M with the surface M¹.

As previously stated, I have shown my invention in preferred form and by way of example, and in connection with a linotype machine. It will be seen that one of the principal features involved is the provision of a movable distributing device controlled 25 as to its position by the form of the type or matrices, and that I preferably employ an intermediate conductor or holder wherein the type or matrices are temporarily stored, and from which they are subsequently delivered 30 to the appropriate channels, and this ordinarily in connection with a plurality of magazines. In the specific form discussed, a separate or individual, and independently movable, conductor or holder is shown, but 35 obviously such an arrangement is not essential, as no invention would be involved in connecting a plurality thereof. This and many other changes and modifications will suggest themselves to those skilled in the art 40 without departure from the scope of the invention.

Having thus described my invention, its construction and mode of operation, what I claim and desire to secure by Letters Patent 45 of the United States is as follows:

1. In a typographical machine, the combination of a plurality of magazines adapted to contain different fonts of type or matrices, distributing mechanism to separate the type or matrices according to letter regardless of 50 font, and a movable device common to the several magazines and adapted to deliver the separated type or matrices into one magazine or another according to font, the said device being controlled in its movement by the form of the type or matrices.

2. In a typographical machine, the combination of a plurality of magazines adapted to contain different fonts of type or matrices, a single distributing mechanism to separate the type or matrices according to letter regardless of font, and an intermediate movable throat or conductor to receive the separated type or matrices and deliver them into one or another of the maga- 65

zines according to font, said conductor being controlled in its movement by the form of the type or matrices.

3. In a typographical machine, the combination of a plurality of magazines adapted to contain different fonts of type or matrices, distributing mechanism to separate the type or matrices according to letter regardless of font, a movable intermediate throat or conductor to receive the type or matrices and deliver them into one or another of the magazines, and means controlled by the form of the type or matrices to move the conductor. 70

4. In a typographical machine, the combination of a plurality of magazines adapted to contain different fonts of type or matrices, distributing mechanism to separate the type or matrices according to letter regardless of font, and a movable device common to the several magazines and adapted to connect with one magazine or another so as to deliver the type or matrices of corresponding font thereto, the said device being controlled as to such connection by the form of the 85 type or matrices. 90

5. In a typographical machine, the combination of a plurality of magazines for the type or matrices, a single distributing mechanism, and an intermediate movable conductor or holder wherein the type or matrices are temporarily stored and from which they are subsequently delivered to one or another of the magazines according to their font. 95

6. In a typographical machine, the combination of a plurality of magazines for the type or matrices, a distributing mechanism, and an intermediate movable conductor or holder wherein the type or matrices are temporarily stored, the said conductor being provided with means to retain the type or matrices for subsequent delivery to one or another of the magazines according to their font. 100

7. In a typographical machine, the combination of distributing mechanism and a movable conductor or holder to which the type or matrices are delivered thereby, the said conductor or holder being provided with means whereby the type or matrices may be released therefrom at one point or another according to their font. 110

8. In a typographical machine comprising distributing mechanism, the combination of a shiftable conductor or holder adapted to contain type or matrices of different fonts, and means for shifting the conductor to different positions so as to deliver the type or matrices at different points according to font, the said means being controlled by the form of the type or matrices. 120

9. In a typographical machine, the combination of a plurality of magazines adapted to contain different fonts of type or matrices, distributing mechanism to separate the type 125

or matrices according to letter regardless of font, a power-actuated device common to the several magazines and movable into operative relation to one or another of the magazines so as to deliver the type or matrices of corresponding font thereto, and means for arresting the said conductor in proper position, the said means being controlled by the form of the type or matrices.

10 10. In a typographical machine, the combination of a plurality of magazines adapted to contain different fonts of type or matrices, distributing mechanism comprising a distributor bar to release all the type or matrices of the same letter, regardless of font,

at the same point, and a movable intermediate conductor pivoted at its upper end so as to receive the released type or matrices and deliver them into one or another of the magazines according to font, the said conductor being controlled in its movement by the form of the type or matrices. 20

In testimony whereof I hereunto set my hand this 6th day of September, 1912, in the presence of two attesting witnesses.

ROBERT OTIS BOARDMAN.
